United States Patent

Des. 242,039
Patented Oct. 26, 1976

242,039

PENCIL WELL

William Macowski, Caldwell, N.J., assignor to
Ketcham & McDougall, Inc., Roseland, N.J.

Filed Mar. 6, 1975, Ser. No. 555,980

Term of patent 14 years

Int. Cl. D19—02

U.S. Cl. D19—85

FIG. 1

FIG. 2

FIG. 3

FIG. 4

FIG. 5

FIG. 6

FIG. 1 is a perspective view of a pencil well showing my new design;

FIG. 2 is a front elevational view;

FIG. 3 is a top plan view;

FIG. 4 is a left side elevational view, the side not shown being a mirror image thereof;

FIG. 5 is a rear elevational view; and

FIG. 6 is a bottom plan view.

I claim:

The ornamental design for a pencil well, as shown and described.
